United States Patent Office.

BENJAMIN J. WARNER, OF BROOKLYN, NEW YORK.

Letters Patent No. 61,127; dated January 8, 1867.

IMPROVEMENT IN WATCH CASES.

The Schedule referred to in these Letters Patent and making part of the same.

TO ALL WHOM IT MAY CONCERN:

Be it known that I, BENJAMIN J. WARNER, of Brooklyn, in the county of Kings, and State of New York, have invented, made, and applied to use, a certain new and useful Improvement in Watch Cases; and I do hereby declare the following to be a full, clear, and exact description of the said invention, reference being had to the annexed drawing, making part of this specification, wherein—

Figure 1 is a cross-section of the case.

Figure 2 is a view representing the case as open; and

Figure 3 is a section through the catch.

The nature of my said invention consists in a ring applied within the lid or cover of the watch case, adapted to the reception of likenesses; said ring being held by a catch so that it may be separated from the lid for the introduction of a likeness, or for viewing a second likeness placed at the back of the first. By this construction I am enabled to safely carry within the watch case two photographic or other likenesses, which are protected from injury, and are in a convenient position for being frequently examined.

In the drawings, *a* is the centre or body of the case to which the shank is attached; *b* is the inner back or cap, which may be made in one piece with the basil, or fitted to open as usual; *c* is the lid, or one of the lids or covers, of any usual kind or material, and hinged to the body *a* at *d*; *e* is a ring hinged also at *d*, and being between the lid *c* and basil *a*. This ring, *e*, is made with a flange receiving the portraits. These portraits or pictures may be on opposite sides of a piece of card or other supporting material, with their surfaces varnished or otherwise protected. I have, however, shown said pictures as introduced between two glasses, (watch crystals,) as at *i i*, and these are held in place within the ring *e*, by the snap-ring *o*.—The spring *r*, that is used to open the lids, acts upon the hinge of said lid through an opening in the hinge of the ring. *s* is the ordinary catch, acted upon by the compression pin through the shank of the case, in any well-known manner, but the catch is larger and projects up through an opening in the ring *e*, and is contiguous to a spring catch, *u*, that holds the ring *e* and lid *c* together. When the catch *s* is pressed back; the lid *c* and ring *e* fly open, exposing the picture next the inner back *b*, but if the ring *e* is held down by the nail, while the catch *s* is pressed back rather further than in the first instance, the catch *n* will be disconnected from the lid *c*, and the case spring will throw the lid *c* back, and expose to view the other portrait, as seen in fig. 2. The ring *e* and lid may be held in place by any usual means, such as snapping instead of having springs as shown.

What I claim, and desire to secure by Letters Patent, is—

The hinged ring *e*, applied between the lid *c*, and body *a*, and fitted for the reception of pictures, and provided with catches, substantially as and for the purposes set forth.

I also claim the ring *o*, snapping outside of the flange of the opening, receiving the glass or crystal and securing the same in place as shown.

In witness whereof I have hereunto set my signature this first day of August, A. D. 1866.

B. J. WARNER.
